(57) **CLAIM**

The ornamental design for a diffuser ring, as shown and described.

DESCRIPTION

FIG. 1 is a perspective view of a diffuser ring according to my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom plan view thereof.

FIG. 8 is a perspective view of a diffuser ring according to another embodiment of my new design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top elevation view thereof; and,

FIG. 14 is a bottom plan view thereof.

1 Claim, 10 Drawing Sheets---
